UNITED STATES PATENT OFFICE.

HERBERT M. STURGIS, OF KANSAS CITY, MISSOURI, ASSIGNOR OF ONE-HALF TO F. E. WEAR, OF KANSAS CITY, MISSOURI.

LOOSE-LEAF DEVICE.

1,011,391.

Specification of Letters Patent. Patented Dec. 12, 1911.

Application filed March 17, 1911. Serial No. 615,086.

To all whom it may concern:

Be it known that I, HERBERT M. STURGIS, a citizen of the United States, residing at Kansas City, in the county of Jackson and State of Missouri, have invented certain new and useful Improvements in Loose-Leaf Devices, of which the following is a specification.

This invention relates to loose leaf books, and has for its object the production of a device of this character which will operate efficiently and reliably and which embodies the desirable features of simplicity, strength, durability and attractiveness of appearance.

With this general object in view and others as hereinafter appear, the invention consists in certain novel and peculiar features of construction and organization as hereinafter described and claimed; and in order that it may be fully understood reference is to be had to the accompanying drawings, in which—

Figure 1, is a plan view of a loose leaf book device embodying my invention. Fig. 2, is an enlarged end view of the same. Fig. 3, is a vertical section on the line III—III of Fig. 1, on a larger scale than Fig. 2. Fig. 4, is a horizontal section on the line IV—IV of Fig. 3, with the device inverted and on a smaller scale than Fig. 3. Fig. 5, is a vertical section on the line V—V of Fig. 1. Fig. 6, is an edge view of a part of one of the rocker plates. Fig. 7, is a detail perspective view of a part of one of the rocker plates. Fig. 8, is a transverse section of a part of the device with the hooks open, the section being on the line VIII—VIII of Fig. 1. Fig. 9, is a detail perspective view of one of the stop blocks of the device.

In the said drawings, 1 indicates a channeled base plate or body of oblong form in plan view and preferably of inverted arch form in cross section, said body being preferably rigid and made of sheet metal and bent at its side margins to form inwardly-opening hooks 2, the marginal upper portions of the hooks terminating in depending lips 3, slightly beyond the ends. The plate is also provided at each end centrally between the lips, with notches 4.

5 indicates end plates fitting against the ends of the body and provided with tongues 6 and held in position by the lips 3 and said tongues, the latter extending upward through the notches 4 and fitting flatly upon

the body 1, as shown clearly in Figs. 3 and 5. The body and ends constitute a rigid frame or casing.

7 indicates a pair of rocker plates fitting at their outer edges in hooks 2 and terminating at their inner edges in longitudinally-extending loops 8, which loops are cut away at suitable points to provide openings 9, shown clearly in Figs. 4, 6, 7, and 8. Formed in said loops and in communication with the openings 9 are openings 10, and adjacent to openings 9, the rocker plates are provided with slightly elongated transverse openings 11.

12 are parallel rods confined within loops 8 and terminating in semi-circular hooks 13 which project outwardly through openings 9 and upwardly through the elongated openings 11, the hooks bearing against the ends of the said openings, and being held reliably in rigid relation to the rocker plates, so that when the latter swing downwardly, opposite hooks will engage at their free ends and constitute rings, the parts being so proportioned that such engagement limits the downward movement of the rocker plates, as shown by dotted lines in Figs. 3, and to maintain the ends of said hooks in perfect alinement when closed, one hook of each pair is preferably formed with a V-shaped notch 14, and the other with a V-shaped end 15, to accurately fit said notch.

To insure synchronous and uniform movement of the rocker plates and to limit their upward movement, an inverted-V shaped stop block 16 fits snugly in each pair of opposite openings 10 and underlies the rocker plates and fits flatly thereagainst when the latter occupy their raised positions, that is, when the rings are open to permit a perforated sheet (not shown) to be placed on or removed from one set of the hooks.

The angle at which the upper or inclined faces of the blocks extend determines the inclination of the rocker plates when elevated, that is to say when the inclined surfaces of the blocks bear flatly against the plates the latter are incapable of further upward movement. The blocks fit so snugly in openings 10 as to be incapable of movement laterally or longitudinally of the rocker plates, but as a precautionary measure, each stop block is provided at its ridge or highest point with a clearly-defined rib 16^a which determines the distance which the

ends of the stop blocks shall project into the openings 10 of the rocker plates.

The loops 8 of the rocker plates are held in rolling engagement at all times by the pressure of a series of springs 17 which fit flatly against the under sides of said plates and bear at their longitudinal edges against the rods 12 and the hooks 2. In the preferred construction, these springs are 5 slightly narrower for the greater part of their length than the spaces between the rods and said hooks, and at their ends are widened at 18 so as to bear against the hooks, the said widened ends being bifurcated at 19 so as to be capable of narrowing under pressure applied on the hooks to either open or close the same. It is manifest the plates are held in either position by the resiliency of the springs 17, by reference to 10 Fig. 3.

To open the rings the operator presses or pulls outwardly on the hooks. In so doing the rocker plates are moved upward and the springs yield by narrowing at their ends 15 until their inner edges pass above the horizontal plane of their outer edges. As this occurs, the springs instantly reexpand and continue the opening movement of the rocker plates until the inclined faces of the 20 blocks 16 fit flatly against the under sides of the rocker plates, in which position the parts will remain until sufficient pressure is applied upon the hooks to overcome the 25 resistance of the springs and return the parts 30 to their original positions.

In the operation of the device, the body may be absolutely rigid, the springs being relied upon to hold the rocker plates depressed with the hooks in closed position 40 or elevated with the hooks in open position, that is to say, the rocker plates when occupying the same horizontal plane are subjected to no inward pressure by the hooks 2 of the body and are held in rolling contact at their 45 inner edges solely by the pressure of the springs.

From the above description it will be apparent that I have produced a loose leaf device embodying the features of advantage 50 enumerated, and while I have illustrated and described the preferred construction, I wish it to be understood that I do not desire to be restricted to the exact details of construction shown and described as obvious 55 modifications will suggest themselves to one skilled in the art.

I claim:—

1. In a loose leaf device, a channeled base plate formed with inwardly opening hooks 60 at its side margins, a pair of rocker plates arranged with their outer edges within said hooks and their inner edges provided with loops in rolling contact, a plurality of hooks carried by said plates adapted for engagement 65 at their free ends to constitute rings,

springs underlying said plates and exerting pressure in opposite directions against the hooks of the base plate and the inner portions of the rocker plates to hold the latter pressed inwardly and in rolling contact at their inner edges and normally out of engagement at their outer edges with the hooks of the base plate, and means connecting the inner edges of the rocker plates together to insure synchronous and uniform movement thereof when the outer ends of their hooks are caused to approach or recede from each other. 70

2. In a loose leaf device, a channeled base plate formed with inwardly opening hooks 80 at its side margins, a pair of rocker plates arranged with their outer edges within said hooks and their inner edges provided with loops in rolling contact, a plurality of hooks carried by said plates adapted for engagement at their free ends to constitute rings, springs underlying said plates and exerting pressure in opposite directions against the hooks of the base plate and the inner portions of the rocker plates to hold the latter pressed inwardly and in rolling contact at their inner edges and normally out of engagement at their outer edges with the hooks of the base plate, means connecting the inner edges of the rocker plates together to insure 85 synchronous and uniform movement thereof when the outer ends of their hooks are caused to approach or recede from each other, and end plates secured to the ends of the base plate outward of the ends of the 90 rocker plates.

3. In a loose leaf device, a channeled base plate formed with inwardly opening hooks 105 at its side margins, a pair of rocker plates arranged with their outer edges within said hooks and their inner edges provided with loops in rolling contact, a plurality of hooks carried by said plates adapted for engagement at their free ends to constitute rings, springs underlying said plates and exerting 110 pressure in opposite directions against the hooks of the base plate and the inner portions of the rocker plates to hold the latter pressed inwardly and in rolling contact at their inner edges and normally out of engagement at their outer edges with the hooks of the base plate, means connecting the inner edges of the rocker plates together to insure synchronous and uniform movement thereof when the outer ends of their hooks are caused to approach or recede from each other, and end plates fitting against the ends of the base plate outward of the 115 ends of the rocker plates; the hooks of the base plate having depending lips engaging 120 the outer sides of the said end plates.

4. In a loose leaf device, a channeled base plate formed at its side margins with inwardly-opening hooks provided at their ends with depending lips, and provided in its 130

- ends between said hooks with notches, end plates fitting against the ends of the base plate and engaged at their outer sides by said lips and provided with tongues extending up through said notches and bearing upon the upper side of the base plate, a pair of rocker plates arranged with their outer edges within said hooks and their inner edges provided with loops in rolling contact, a plurality of hooks carried by said plates and adapted for engagement at their free ends to constitute rings, springs underlying said plates and exerting pressure in opposite directions against the hooks of the base plate and the inner portions of the rocker plates to hold the latter pressed inwardly and in rolling contact at their inner edges and normally out of engagement at their outer edges with the hooks of the base plate, and means connecting the inner edges of the rocker plates together to insure synchronous and uniform movement thereof when the outer ends of their hooks are caused to approach or recede from each other.
5. In a loose leaf device, a channeled base plate formed with inwardly opening hooks at its side margins, a pair of rocker plates arranged with their outer edges within said hooks and their inner edges provided with loops in rolling contact, a plurality of hooks carried by said rocker plates adapted for engagement at their free ends to constitute rings, springs underlying said plates and exerting pressure in opposite directions against the hooks of the base plate and the inner portions of the rocker plates to hold the latter pressed inwardly and in rolling contact at their inner edges and normally out of engagement at their outer edges with the hooks of the base plate, and a plurality of transversely extending blocks extending through the inner edges of the rocker plates to compel the same to move together; said blocks having upwardly converging faces to fit flatly against the undersides of the rocker plates when the latter are elevated and prevent further upward movement thereof.
6. A loose leaf device, comprising a channeled base plate having inwardly-opening hooks at its side margins, rocker plates fitting at their outer edges within said hooks and formed at their inner edges with longitudinally extending loops provided at suitable points with openings, inverted-V-
- shaped blocks arranged with their apices in the plane of the contact of the loops and projecting through the openings of the latter, and springs interposed between the loops of the rocker plates and the hooks of the base plate to hold said loops in rolling contact.
7. A loose leaf device, comprising a channeled base plate having inwardly-opening hooks at its side margins, rocker plates fitting at their outer edges within said hooks and formed at their inner edges with longitudinally-extending loops provided at suitable points with openings, opposite hooks rigid with said rocker plates and adapted to fit together at their free ends to constitute rings, inverted-V-shaped blocks projecting through the openings of the loops and each provided between said loops and above the axial centers thereof with a rib incapable of slipping through said openings, and springs holding the loops in rolling contact.
8. In a loose leaf device, a channeled base plate having inwardly-opening marginal hooks terminating in downturned lips beyond the ends of the body of the base plate and end plates fitting against the ends of the body and between the same and the lips of said hooks.
9. In a loose leaf device, a channeled base plate having notches in its ends and inwardly-opening hooks at its side margins terminating beyond the ends of the body of the base-plate in downturned lips and end plates fitting against the ends of the body and clamped thereagainst by said lips and provided with tongues projecting inwardly from their lower edges through said notches and resting inward of the latter upon the base plate.
10. In a loose leaf device, a rocker plate formed at one edge with a loop, and near the ends of said loop with transversely-extending openings, a rod fitting in said loop and bent at its ends to form similar hooks, said hooks extending outwardly from the loop and upwardly and outwardly through and bearing against the opposite ends of said openings.
